UNITED STATES PATENT OFFICE.

FRANZ A. FULLER, OF NEWARK, NEW JERSEY, ASSIGNOR TO THE J. E. MERGOTT COMPANY, OF NEWARK, NEW JERSEY, A CORPORATION OF NEW JERSEY.

BAG-FRAME.

1,240,557.

Specification of Letters Patent. Patented Sept. 18, 1917.

Application filed November 13, 1915. Serial No. 61,214.

To all whom it may concern:

Be it known that I, FRANZ A. FULLER, a citizen of the United States, residing in the city of Newark, in the county of Essex and State of New Jersey, have invented certain new and useful Improvements in Bag-Frames, of which the following is a full, clear, and exact description, such as will enable others skilled in the art to which it pertains to make and use the same, reference being had to the accompanying drawings, and to letters of reference marked thereon, forming a part of this specification.

This invention relates to improvements in bag frames, particularly to the type in which an intermediate frame member is employed, and has for its object, an improved method of securing the leather or fabric of which the partition is formed, to the intermediate frame member, thereby dispensing with the ordinary filling plate or inlay, which was held in position by means of rivets.

In carrying out my invention, I make use of the structure illustrated in the accompanying drawings, in which

Figure 1 represents a side elevation of a purse in closed position, embodying the principles of my invention.

Fig. 2 represents an end elevation of my improved purse, showing the outside frame members in an angular position.

Fig. 3 represents an enlarged sectional, fragmentary view taken on line X of Fig. 1, looking in the direction indicated by the arrow; and

Fig. 4 represents an enlarged sectional, fragmentary, perspective view of the intermediate frame member.

Similar letters of reference refer to like parts throughout the specification and drawings.

In the drawings, *a* and *b* represent the usual outside pair of frame members, and *c* the usual intermediate frame member, which are pivotally secured at their lower end portions by means of suitable pins or rivets *d*, or they may be pivotally connected with each other in any other well-known manner.

The outside frame members *a* and *b*, each comprising a main body portion and end members extending therefrom, are formed from an unbroken flat piece of sheet metal, and so formed by means of suitable punches and dies, that a continuous integral, down-

wardly-extending narrow flange *e*, extending around the inner edge of said body portion and the end members, is formed. The intermediate portion of the main body portion and end members, between the upper 60 and lower portions of the frame member, is preferably beveled, as clearly indicated in the drawings.

The bag body *f* itself is cut to the shape of the members *a* and *b*, and is secured 65 thereto by means of the filling-in plates *g*, which are secured to the frame members by means of rivets *h*.

The intermediate frame member *c* comprises a main body portion and end members extending therefrom, formed from an unbroken flat piece of sheet metal, and having formed along the top of its entire length, an upwardly-extending flange *i*, bylapping or folding the metal together, to provide 70 rigidity and stability to the frame member. Below the flange *i*, the intermediate frame member is provided with the convex portions *k*—*k*, which are preferably left open, as indicated in Fig. 4 of the drawings, and 75 the opening being of sufficient width to receive the margin of the partition *l*, which may be leather or fabric, after which the edges of the convex portions of the intermediate frame member *c* are pressed together, so as to grip the margin of the partition. In this way, the material from which the partition is made, is held firmly secured to the intermediate frame member without any liability to separate, and with- 80 out the use of filling plates and rivets.

The shape or configuration of the flange *i* of the intermediate frame member, can be made to conform to any desired shape of the frame members *a* and *b*, and is preferably made of a width so that when the frame members are in their closed position, as illustrated in Fig. 3 of the drawings, said flange projects slightly above the frame members *a* and *b*. The flanges *e* of the 85 frame members *a* and *b* are preferably made of such a depth as to engage with the flange *i* of the intermediate frame member, and to permit the convex portions *k*—*k* of the intermediate frame member to be received 90 into the frame members *a* and *b*.

It will thus be seen that I have provided a novel and serviceable means for securing the partition of the bag body to the intermediate frame member, in such a way as 110

to accomplish fully the results sought for, namely, that of firmly securing the partition to the intermediate frame member without the liability of its accidental separation in ordinary or reasonable use, without the use of filling plates and rivets.

Experience has demonstrated that the organization above described is a practical and highly efficient one, and while the structure described is the preferred embodiment of my present invention, I do not care to restrict myself to the exact details of construction, combination and arrangement herein set forth, it being obvious that minor variations thereof, not involving the exercise of invention, may be made by any skilled mechanic, and such departures from what is herein described and claimed, not involving invention, I consider within the scope and terms of my claims.

I claim:

1. In a device of the character described, two outside bag frame members, an intermediate bag frame member, and means for pivots connecting the lower ends of said bag frame members, the outside bag frame members each comprising a channeled strip formed from an unbroken flat piece of sheet metal, and a continuous flange extending around the inner edge of each of said members, the intermediate frame member comprising a channeled strip provided with convex portions formed from an unbroken

flat piece of sheet metal, and provided with a continuous flange extending around the upper portion of said frame member, the flange of said intermediate member being formed by folding the metal of said frame member together and adapted to lie between the continuous flanges of the outside frame members and projecting beyond said frame members.

2. A hand bag comprising two outside frame members, an intermediate bag frame member and means for pivotally connecting the lower ends of said bag frame members, the intermediate frame member comprising a channeled strip formed from an unbroken flat piece of sheet metal, and provided with a continuous flange formed by folding the metal of said frame member together and extending around the upper portion of said frame member, the channeled strip forming a hollow open channel throughout the length of the intermediate member, a partition secured within the open channel of said strip, said channeled member being adapted to close upon and grip the margin of the partition, for securing the edge of said partition in position.

This specification signed and witnessed this 11th day of November, 1915.

FRANZ A. FULLER.
